PUMPS OF THE AIR DISPLACEMENT TYPE

Frederick Walter McCombie, London, England, assignor to Megator Pumps and Compressors Limited, London, England

Filed Dec. 10, 1957, Ser. No. 701,768

Claims priority, application Great Britain Dec. 13, 1956

2 Claims. (Cl. 103—242)

This invention relates to pumps of the air-displacement type, i.e. to pumps wherein the liquid, often a liquid which is difficult to handle with ordinary pumps, is displaced by air or other gaseous medium hereinafter referred to as air for convenience of description.

Such pumps include a chamber having inlet and outlet valves near the bottom and a connection at the top through which air can be evacuated to draw the liquid into the chamber and admitted under pressure to force the liquid out of the chamber.

It is present practice to control the evacuation and admission of air in accordance with the level of the liquid in the chamber by means of floats. Such floats are generally unreliable in operation as they are subject to sticking, corrosion and incrustation.

The chief object of this invention is to evolve a generally improved construction of air-displacement type pump which does not rely on such floats for its successful operation.

A pump of the air-displacement type is characterized in accordance with present invention in that the chamber is movable in a vertical direction in accordance with the weight of the contained liquid, thereby actuating the valve controlling the evacuation and admission of air to the chamber directly or indirectly.

The weight of the empty chamber is balanced by a counterweight or spring so that the chamber rises as it empties and falls as it fills.

Consequently, the terminal movement of the chamber in an upward direction may be arranged to open the air valve controlling evacuation of the chamber and thus allow the chamber to fill with liquid and commence to fall, the terminal movement of the chamber in a downward direction being used to open the valve admitting air under pressure to expel the liquid.

It will be appreciated that the air valves may be actuated by the movement of the chamber through mechanical means, or indirectly through limit switches or pilot valves.

The air connection to the chamber may be made by a further tube or pipe which again may be of a flexible character, or may be otherwise arranged to allow unrestricted movement of the chamber in a vertical direction.

Referring to the drawings:

Figures 1 and 2 are diagrammatic views illustrating the construction of an air-displacement type pump in accordance with the invention; and

Figures 3 and 4 are fragmentary views illustrating two modifications.

Referring in the first case to Figures 1 and 2, the pump comprises a fixed casing 1 having inlet and outlet connections 2 and 3 at its opposite ends and a further connection 4 at an intermediate point. The flow of liquid through the fixed casing is under the control of inlet and outlet non-return valves 5 and 6, these valves normally maintaining a closed position under the action of gravity.

2

A flexible pipe 7 is connected with outlet connection 4, this pipe 7 leading to a chamber 8 which is pivotally connected at 9 to a steelyard 10 having a fulcrum point 11 and carrying an adjustable weight 12 which wholly or partly balances the weight of chamber 8. A spring may be used instead of or in addition to weight 12.

The free end of the steelyard 10 is pivotally connected at 13 to a link 14 which in turn is pivotally connected at 15 to a lever 16 associated with a three-way valve 10 mounted in a valve casing 17.

The lever 16 has associated with it an upstanding lever 18 carrying a weight 19.

A pipe connection 20 is taken from the valve casing 17 to a connection 21 on the upper end of the chamber 8, the pipe 20 terminating in a flexible pipe 22 which is itself connected with the part 21.

The valve casing 17 has a connection 23 for the entry of air under pressure and a further connection 24 to atmosphere or vacuum.

20 In the construction shown in Figures 1 and 2, liquid can enter the fixed casing 1 via the inlet connection 2 and displace valve 5 into the position shown, the connection 4, flexible pipe 7 and chamber 8 then filling with liquid, the air being displaced from chamber 8 as a result

25 of pipe 20 being connected to atmosphere or vacuum through the medium of the three-way valve. When a sufficient weight of liquid has entered chamber 8, chamber 8 will move downwardly under the weight of the contained liquid and against the action of the weight 12,

30 and consequently lever 18 together with its weight 19 will be moved over a dead centre position into the position shown in Figure 2. The pipe 20 and the interior of chamber 8 will then be connected with a source of compressed air supply through the medium of the three-way

35 valve which has moved through an angle of 90° and consequently the liquid contained in chamber 8 and its associated flexible pipe 7 and connection 4 will be displaced downwardly, causing valve 5 to close and valve 6 to open, and will so be discharged from the outlet connection 3. Owing to the reduction of weight resulting

40 from the discharge of the liquid from chamber 8 and pipe 7, the chamber will now rise and operate the three-way valve, so that the pipe 20 is again connected to the atmosphere or vacuum and the cycle repeated.

45 Although a rotating three-way valve is shown by way of example, any suitable kind of valve may be used.

As shown in Figures 1 and 2, the chamber 8 is of cylindrical form and is connected with the fixed casing through the medium of a flexible pipe 7. It may be desirable in some cases to avoid the use of this cylindrical chamber 8, in which case the necessary weight of liquid can be entirely contained in a long pipe bent or folded back on itself or wound in a coil or helix as shown in Figure 3. The helical pipe 25 is closed at its upper end by a closure member 26 which in turn is pivotally connected at 9 with the steelyard 10. It will be seen that the lower end of the pipe 25 is connected directly with connection 4 associated with the fixed casing.

Such an arrangement is simple to make and easy to flush out for cleaning and has the advantage that the pipe 25 can be comparatively long, thus giving great flexibility and also enabling a considerable volume of liquid to be contained in its convolutions.

85 The steelyard 10 again carries a weight 12 by means of which the weight of the helical pipe is partly balanced, the free end of the steelyard being connected with the three-way valve through the medium of a link 14 as in the previously described arrangement.

70 It will be seen from Figures 1, 2 and 3 that the pipe 7 or 25, where it joins connection 4, lies substantially horizontally, thus avoiding any material vertical re-

action on the pipe arising from the pressure of the liquid which would make the working of the mechanism vary with every variation of pressure or vacuum, instead of being controlled entirely by the weight of liquid in the pipe. The pipe preferably has, however, a slight slope 5 downwards towards the connection 4 to facilitate drainage.

It will be appreciated that in the previously described construction illustrated by Figures 1 and 2, the pipe 7 is necessarily of a flexible character, as in order to operate 10 the valve direct, the chamber 8 must have a substantial movement in a vertical direction.

The arrangement shown in Figure 4 has, therefore, been designed to permit of satisfactory operation with a pipe 7 composed of a more rigid material such as metal 15 or glass. Such a pipe composed of a more rigid material will, if correctly designed, be capable of a small degree of longitudinal flexure which will be sufficient to initiate the operation of a suitable valve.

In such a case, the steelyard 10 again carries a balance weight 12 and is also connected with a fixed point by means of a coil spring 27 and an adjusting device 28, whereby the balance of the chamber 2 can be accurately determined.

In this construction, however, instead of operating the 25 valve direct, the valve is electrically actuated and comprises a solenoid operated three-way valve 29, the windings of the solenoid being connected by leads 30 with a pair of micro switches 31 and 32 arranged on opposite sides of the steelyard. At least one of the micro switches 30 31 and 32 may be adjustable vertically by means of a finger-actuated adjusting nut 33 associated with a fixed part of the apparatus.

With this arrangement, by suitable adjustment of the adjusting devices 28 and 33, the valve 29 can be operated 35 with only a minimum of upward and downward movement of the chamber 8 and longitudinal flexure of the pipe 7.

It will be noted that the weights 12 and 19 and the spring 27 which balance the weight of the chamber and 40 liquid are adjustable so as to compensate for the differing specific gravities of different liquids that may be pumped. These adjustments may also be used, in cases where it is desired to cleanse the pump completely after use, by pumping a cleansing liquid through it, so that 45 the cleansing liquid is made to rise slightly higher in the chamber than the pumped liquid.

The pipe 7 or 25 may be composed of metal, glass, rubber or other suitable material and may with advantage be partly or wholly transparent, thus enabling the level of liquid within the pipe to be observed. For example, pipes 7 and 25 may be composed of a transparent or substantially transparent thermo-plastic material such as, for example, polyethylene, methyl methacrylate, polyvinylchloride, nylon or other suitable material.

I claim:

1. A pump of the air displacement type comprising a helical tube defining a chamber, the lower end of said tube being fixed, said tube being flexible with the upper end thereof being movable in accordance with the weight of a liquid contained within the coils thereof, a pipe in communication with the upper end of said tube for evacuating air therefrom and admitting air thereinto, a valve connected to said pipe and controlling the evacuation and admission of air to the chamber, means operatively connected with the upper end of said tube for controlling said valve to evacuate air when said end is in the upper position and admit air when it is in a lower position, and liquid connection means in communication with the lower end of said tube.

2. The pump of claim 1 wherein said tube is constructed of a thermoplastic material, said valve controlling means including counterbalancing means attached to the upper end of said tube for raising it upon removal of the liquid therefrom.
